UNITED STATES PATENT OFFICE.

GEORGE R. RULAND AND WILLIAM W. GREEN, JR., OF BYRON CENTER,
NEW YORK.

IMPROVEMENT IN CIDER-MILLS.

Specification forming part of Letters Patent No. 43,229, dated June 21, 1864.

To all whom it may concern:

Be it known that we, GEORGE R. RULAND and WILLIAM W. GREEN, Jr., of Byron Center, in the county of Genesee and State of New York, have invented certain new and useful Improvements in Cider-Presses; and we do hereby declare that the following is a full and exact description thereof, reference being had to the accompanying drawings, making part of this specification.

Figure 1 is a side elevation of our improved machine; Fig. 2, a central longitudinal vertical section; Fig. 3, a transverse vertical section in the plane of line $x x$, Fig. 1; Fig. 4, a plan of two sections of the lower endless platform or bed; Fig. 5, a diagram representing the intermatching of the sections of the upper and lower platforms for the purpose of expressing the cider; Figs. 6 and 7, a plan and end view, respectively, of two sections of the upper endless platform.

Like letters of reference indicate corresponding parts in all the figures.

Our invention consists, essentially, in expressing cider from pomace by passing the latter between two endless platforms, so arranged that their contiguous surfaces come nearly in contact; also, in the construction, arrangement, and combination of the parts connected with said platforms, as hereinafter set forth.

As represented in the drawings, A is a suitable frame, in which at suitable distance apart are mounted longitudinally two pairs of ways, B B and C C, around which the upper and lower platforms, D and E, respectively, travel. In general construction these platforms resemble those used in treadhorse-powers, being made of sections $a a' a' a$, and jointed by friction-rollers $b b$, that run on the ways. The lower platform or bed, E, is driven conveniently by means of pinions $c c$ on the shaft of cog-wheel d , which pinions gear on opposite sides with cog-racks $e e$, secured to the sections $a' a'$, as shown most clearly in Figs. 2 and 3. Cog-wheel d is operated by means of pinion q on a shaft driven by band-pulley r . The upper or pressing platform, D, is driven merely by the friction that is produced by its coming in contact with the lower platform. The ways B B of the upper platform are hung at the induction end on a transverse bearing, f , Figs. 1 and 2, while at the opposite end they are adjusted

down vertically by any convenient means, that represented in the drawings being screw-rods $i i$, secured to the frame below, and passing up through projections $g g$ on the sides of the ways, and having nuts $h h$ secured at the top, between which and the projections are situated rubber springs $k k$, to allow the platform to yield if any foreign body, such as a stone, should pass through. The upper surface or bed of the lower platform is preferably level, or nearly so; but the contiguous or pressing surface of the upper platform is somewhat convex, so that while the central portion is pressing on the pomace to extract the juice the induction and ejection ends are both open for the introduction and discharge of the pomace. The relative connection of the two platforms is clearly exhibited in Figs. 1 and 2. The sections $a' a'$ of the lower platform are made sufficiently larger than the section $a a$ of the upper platform to allow cleats $l l$, or equivalent, to be secured crosswise at the ends of the former, to form shoulders, as represented in Figs. 4 and 5. Between these cleats the sections of the upper platform fit, Fig. 5, so as to nearly come in contact with the floor of the bed. Between the upper and lower platforms runs an endless apron, G, made of canvas or other suitable porous material. This apron passes over four rollers, $m m m m$, at suitable positions to carry the said apron around the lower platform, and to project it sufficiently in front and rear to properly receive and discharge the pomace. One of the rollers is driven by means of a pulley, n , which receives motion by a band, o , connecting it with a pulley, p , on the shaft of cog-wheel d . The sides of the endless apron project somewhat beyond the ends of the section, so as to retain the pomace between the platforms, as shown in Fig. 5.

Through the sections $a' a'$ of the lower platform are made a series of openings, $s s$, Figs. 2, 4, and 5, either in the form of slots, as shown, or perforations, so that the cider, as it is expressed by the platforms and strained by the canvas apron, will readily flow through into a receptacle or trough, H, Figs. 2 and 3, between the ways C and within the lower platform, E. From this receptacle or trough the cider escapes through a lateral spout, t , into a suitable tub outside.

Between the sections *a a* of the upper platform, and secured to the sides which close together, are strips *u u*, Figs. 6 and 7, of rubber or other suitable packing, whose office is to close or pack the joint when the sections come downward into the position for pressing the pomace, and thus prevent the juice from passing through. Similar strips, *u' u'*, are used between the ends of the cleats *l l* of the sections *a' a'* of the lower platform, but not between the sides of the sections, for it is designed to leave them open for the passage of the cider into the receptacle or trough *H*. The use of the strips *u' u'* is to prevent the escape of the cider laterally through the ends, as it is expressed by the platforms.

The operation of this machine is at once manifest. The pomace is fed in at the left hand in the drawings, and in passing between the platforms is thoroughly pressed, and after having passed through, it drops off the canvas at the opposite end. The platforms are far superior to any arrangement of rollers with a canvas apron passing between them in several respects. When rollers are used, the pomace does not pass through readily, but the rollers force or slide it back. In our device there is no difficulty of this kind for the entrance is so gradual and the opposite sections close so nearly on a level that the pomace cannot slide back. Where rollers are employed, the pressure is exerted only at the point of contact of the rollers, and therefore is very slight and ineffectual. In our device a long bearing of the two platforms is produced, so that the cider cannot fail of being thoroughly expressed. The flat surfaces of the sections meeting together exert a greater and more effectual pressure than can be produced by convex rolling-surfaces. The vertical adjustment of the upper ways, *B*, enables us to graduate the pressure exactly as required. The slots or openings *s s* allow the cider to pass freely through into the receptacle or trough *H*, so that it freely escapes. The cleats *l l*, between which the sections of the upper platform fit, prevent the pomace from being forced out laterally, confining it in the inclosed space so as to receive the best effect of the pressure, while the

packing strips *u* and *u'* prevent the juice from flowing through the upper sections and the ends of the lower ones.

What we claim as our invention, and desire to secure by Letters Patent, is—

1. The combination of two endless platforms, *D E*, and an endless apron, *G*, passing between them, said platforms being so arranged as that their contiguous surfaces shall come nearly in contact to produce pressure, substantially as and for the purposes herein set forth.

2. Making the lower sections, *a'*, longer than the upper sections, *a*, and providing their ends with the cross cleats or shoulders *l l*, between which the said upper sections, *a*, match and fit, for the purpose of confining the pomace during the act of pressing, substantially as herein set forth.

3. Hanging the ways *B B* of the upper platform on a bearing, *f*, at one end, and adjusting the other end down to increase the pressure by means of the rods *i i*, projections *g g*, and nuts *h h*, or some equivalent means, substantially as and for the purpose herein specified.

4. Providing the sections *a' a'* of the lower endless platform with openings or perforations *s s*, whereby the cider can escape through, substantially as herein described.

5. The receptacle or trough *H*, situated between the ways *C C*, and inclosed by the lower endless platform, *E*, said receptacle or trough being so situated as to catch the expressed cider and discharging it by a suitable spout, substantially as described.

6. The packing-strips *u* or *u'*, in combination with the sections *a a* or the cleats *l l*, so arranged that when said sections or cleats close in the act of pressing the packing strips will shut off the passage of the cider, substantially as herein set forth.

In witness whereof we have hereunto signed our names in the presence of two subscribing witnesses.

GEO. R. RULAND.
